UNITED STATES PATENT OFFICE.

GRIGORI PETROFF, OF NOVO GIREEVO, RUSSIA.

PROCESS FOR HYDROLYZING FATS AND FATTY OILS INTO GLYCERIN AND FATTY ACIDS.

1,079,437.

Specification of Letters Patent. Patented Nov. 25, 1913.

No Drawing.

Application filed July 5, 1912. Serial No. 707,753.

To all whom it may concern:

Be it known that I, GRIGORI PETROFF, a subject of the Czar of Russia, and residing at Novo Gireevo, Moscow-Nizhni Railway Line, Eleninsky Prospect, Dom. Troitzky-Kusminoy, Russia, have invented certain new and useful Improvements in the Process for Hydrolyzing Fats and Fatty Oils into Glycerin and Fatty Acids, of which the following is a specification.

This invention relates to an improved process for the hydrolytic decomposition of fats and fatty acids into glycerin and fatty acids.

The improved process consists in using for this purpose the organic sulfonic acids obtained from mineral oils, such as crude petroleum or its distillates. These sulfonic acids possess as splitting agents great advantages over the agents hitherto ordinarily employed in the art for the hydrolysis of fats.

It has been known for a long time that organic sulfonic acids are formed by the action of concentrated sulfuric acid or sulfuric acid anhydrid upon crude petroleum, the distillates thereof or the like. These sulfonic acids may be separated out from the sulfonation products in various ways, and be obtained in a more or less pure form.

For instance, the sulfonated naphtha hydrocarbons may be washed with an aqueous lye after the deposition of the precipitated acid tar layer (Goudron layer), as is usually done for instance in refining naphtha distillates. In this operation the sulfonic acids pass over in the form of salts into the aqueous solution from which the hydrocarbons which are carried over with them are removed by means of benzine, benzol or other solvents. The solution thus purified is composed by means of an excess of concentrated sulfuric acid. In this operation the sulfonic acids are separated out in the form of a thick layer which contains only some water and sulfuric acid. In this form the acids can be employed for splitting the fats. If such commercially pure sulfonic acids are digested with ether or benzol, only the sul-

fonic acids will become dissolved therein which have remained behind in a chemically pure state after the removal of the solvents. Such pure sulfonic acids form a solid or semi-solid resin-like hygroscopic mass, according to the properties of the initial material and also according to the

degree of sulfonation. Said mass contains a mixture of various sulfonic acids of cyclic hydrocarbons which latter have a very high molecular weight. I have now discovered that aqueous solutions of such sulfonic acids have a distinctly pronounced property of splitting fats into glycerin and fatty acids, and that for this purpose very small amounts (0.5 to 1.0%), of such splitting agent are sufficient. The splitting action and the speed of reaction increase with increase in the temperature and with the molecular weight of the sulfonic acids. The splitting action is also favored and accelerated by the presence of small quantities of some mineral acids.

The following example may be given of a preferred manner of carrying out the present process. 40 parts by weight of water, 0.25 parts of concentrated sulfuric acid, 0.75 parts of the above mentioned sulfonic acids, and 100 parts of melted fat or oil are poured in succession into a wooden or lead-lined iron vessel provided with a pipe for admitting steam or water vapor. By admitting steam the mixture is caused to boil and is kept boiling continuously for some hours. With the stated proportions by weight, more than 90% of the glycerids are split up after a lapse of 5 to 10 hours. The boiling is then stopped and the fatty acids are allowed to separate out from the glycerin water and further treated in the usual manner for the production of stearin or soap. The sulfonic acids employed for splitting remain in solution in the glycerin water. The latter is neutralized with lime or barium hydroxid. The precipitate is separated by filtration, and the filtrate is treated in the usual manner for the recovery of glycerin. The precipitate is treated with sulfuric acid for the recovery of the sulfonic acids which can then be used over again as hydrolyzing agents as above described.

The use of sulfonic acids for splitting fats has very many advantages over the well-known agents, for example, the aromatic sulfonic fatty acids, employed in the Twitchell process, which are produced by the action of sulfuric acid upon a mixture of non-saturated aliphatic acids with aromatic hydrocarbons. The sulfonic acids which are separated out from sulfonated naphtha-hydrocarbons, possess a greater splitting power, so that by their use the du-

ration of the reaction and also the quantity of the splitting agent can be considerably diminished. The resulting fatty acids are much lighter than those obtainable by the 5 Twitchell process. Further, the splitting agent according to this invention can be regenerated or recovered after each operation, so that a comparatively very small quantity is sufficient for the decomposition of a considerable amount of fat.

Claims.

1. A process for splitting fats and oils into glycerin and fatty acids, which consists in using as splitting agents the sulfonic acids which are formed and isolated in the treatment of mineral oils or their distillates with concentrated sulfuric acid or its anhydrid.
2. A process for splitting fats and oils into glycerin and fatty acids, which con-

sists in mixing the fat or oil with the necessary quantity of sulfonic acids of mineral oil hydrocarbons and effecting hydrolysis of the fat or oil in the presence of water in an acid medium.

3. A process for splitting fats and oils into glycerin and fatty acids, which consists in mixing the fat or oil with the necessary quantity of sulfonic acids of mineral oil hydrocarbons and effecting hydrolysis of the fat or oil in the presence of water in an acid medium with agitation of the mixture by steam or air.

In testimony whereof I have signed my name to this specification in the presence of 35 two subscribing witnesses.

GRIGORI PETROFF.
